(No Model.)

A. H. MOORE.
FAN ATTACHMENT.

No. 296,346.

Patented Apr. 8, 1884.

Fig. 1.

UNITED STATES PATENT OFFICE.

ARTHUR H. MOORE, OF CHICAGO, ILLINOIS.

FAN ATTACHMENT.

SPECIFICATION forming part of Letters Patent No. 296,346, dated April 8, 1884.

Application filed December 26, 1883. (No model.)

To all whom it may concern:

Be it known that I, ARTHUR H. MOORE, of Chicago, county of Cook, and State of Illinois, have invented a new and useful Automatic 5 Fan Attachment for Rocking-Chairs, of which the following is a full and complete description, reference being had to the accompanying drawings.

My invention relates to an automatic fan 10 attachment for rocking-chairs, in which, by means of a rack and pinion and auxiliary mechanism, the vibratory motion in the operation of rocking produces a reciprocating movement of rotary fans.

15 In the drawings, Figure 1 is a perspective view of a chair with my improvement attached. Fig. 2 is a detail view showing portions of the fan mechanism. Fig. 3 shows a bayonet-catch sleeve, the object of which is 20 hereinafter set forth. Fig. 4 shows a bevel-gear modification of parts shown in Fig. 1. Fig. 5 is a transverse section through line xx , Fig. 2. Fig. 6 is a vertical section partially showing the lower portion of Fig. 3.

25 In the present example I have illustrated my fan attachment in connection with a chair known as the "patent rocker"—*i. e.*, in which the chair is mounted upon a base, on which latter the rockers of the chair have their 30 bearings.

A represents the base aforesaid, and A' represents the rockers of the chair.

The upper portions, A², of the chair are 35 sufficiently outlined for the purpose of description.

Near the top of the chair-back are secured 40 bearings a_1 , in which a shaft, A³, is located. In a position corresponding to shaft A³ are forwardly-extending supports or arms a' , on which are attached bearings a^2 . The latter 45 serve as supports for rods or shafts A⁴, on which are located the rotary fans A⁵.

A⁶ represents a rack, and A⁹ a pinion. The latter is secured on shaft A³. Hinged at a^3 to 50 a cross-piece, a^4 , of base A is a vertical tubular shaft, A⁷. Rack A⁶ is provided with a cylindrical lower termination or piston, a^5 , extending into the cavity of shaft A⁷.

To provide for throwing the fans "in and out 55 of gear" the upper end of shaft A⁷ is provided with a vertical slot, a^{10} , Figs. 5 and 6, and cylinder or piston a^5 has inserted at right

angles to its length a pin or projection, a^6 . In the tubular shaft A⁷ is also inserted a pin or projection, a^7 .

To engage pins a^6 and a^7 and form a rigid connection between the shaft A⁷ and piston a^5 , a bayonet-catch sleeve, A⁸, is provided. The latter is vertically slotted to a distance corresponding to the length of the vertical slot in 60 the tubular shaft A⁷. Transverse slots b' and b^2 , corresponding in position to pins a^6 and a^7 , permit a lateral movement of sleeve A⁸. When sleeve A⁸ is so adjusted that its vertical slot corresponds in position to the vertical slot in 65 shaft A⁷, the pin a^6 , which corresponds in position thereto, would travel up and down in said slots without producing any movement of the rack and pinion with relation to each other; but when sleeve A⁸ is laterally moved 70 so that pin a^6 engages with slot b' , (more plainly shown in Fig. 3,) a connection is formed that necessitates the movement of rack A⁶ with relation to pinion A⁹ when the chair is rocked. Guide-bars b^3 , between which and the rack A⁶ 75 the shaft A³ passes, serve to keep said rack in position with the pinion.

To permit arms a' to be elevated to a vertical position when it may be desirable to remove the fans from their lateral position and 80 out of the way, said arms are hinged at a^2 , and provided with any convenient mechanism for raising and lowering them.

Shaft A³, as shown in Fig. 1, is coupled 85 with shaft A⁴ by means of a flexible coupling, a^8 . In Fig. 4 I have also shown a bevel-gear as a modification of the same.

It is obvious that when a connection is formed by means of sleeve A⁸, and a movement thus established between the rack and 90 pinion when the chair is rocked, a reciprocating rotary movement is given to shaft A³, and, by means of the flexible coupling a^8 or bevel-gear a^9 , to shaft A³, and consequently to fans A⁵.

Having thus fully described my said invention, what I claim, and desire to secure by Letters Patent, is—

1. In combination with fans A⁵, the shafts A³ and A⁴, rack and pinion A⁶ A⁹, hinged 100 to shaft A⁷, and flexible coupling a^8 , or its equivalent, substantially as and for the purpose set forth.

2. The combination of fans A⁵, shafts A³

and A^4 , rack and pinion A^6 and A^9 , flexible coupling a^9 , or its equivalent, tubular hinged shaft A^7 , and the connecting-sleeve A^8 , substantially as and for the purpose specified.

5 3. In combination with fans A^5 , the shafts A^3 and A^4 , flexible coupling a^9 , rack and pinion A^6 A^9 , hinged shaft A^7 , and the hinged arms

a' , substantially as and for the purpose described.

ARTHUR H. MOORE.
